WING-FUSELAGE FAIRING

Walter T. Brownell, Mount Prospect, Ill.
Application February 1, 1956, Serial No. 39,989

Term of patent 14 years
(Cl. D71—1)

FIG. 1

FIG. 2

FIG. 4

FIG. 3

Fig. 1 is a side elevational view of a wing-fuselage fairing showing my new design;

Fig. 2 is a top plan view of the fairing; and

Figs. 3 and 4 are front and rear elevational views thereof, respectively.

The broken line showings in the several views are for illustrative purposes only.

I claim:

The ornamental design for a wing-fuselage fairing, substantially as shown and described.
